UNITED STATES PATENT OFFICE.

HENRY CHARLES MILLER, OF MILWAUKEE, WISCONSIN.

LOOSE-LEAF BINDER.

1,240,356.

Specification of Letters Patent. Patented Sept. 18, 1917.

Application filed February 23, 1917. Serial No. 150,409.

To all whom it may concern:

Be it known that I, HENRY C. MILLER, a citizen of the United States, and resident of Milwaukee, in the county of Milwaukee and State of Wisconsin, have invented, certain new and useful Improvements in Loose-Leaf Binders; and I do hereby declare that the following is a full, clear, and exact description thereof.

10 My invention relates to new and useful improvements in loose leaf binders of that general type including a pair of binder heads and connecting members for the heads having portions flexible throughout and 15 movable into one of the heads to provide for adjustment of one of the connecting members between the heads.

One disadvantage of loose leaf binders of this type heretofore contemplated and embodying means for mechanically extending 20 and retracting the flexible connecting posts has been the loss of time and labor incidental to the releasing actuation of such mechanical means. In such types of binders contemplating 25 a manually operable means for manipulating the flexible connecting posts, it is difficult to obtain the desired clamping action which a mechanical actuating means, usually embodying a right and left hand 30 feed shaft, affords.

It is therefore primarily the object of my invention to provide a mechanical means for moving the connecting posts into and out of a binder head, with which the posts are connected in such manner as to permit their 35 very ready detachment therefrom. More specifically in this connection, it is my object to provide a mechanical operating means for the connecting posts which is automatically 40 detachable from the posts upon operation thereof to feed the posts outwardly, whereby the posts may be readily released for manual movement relative to the binder head upon movement of the binder heads 45 apart, and further wherein the operating means is automatically reengageable with the posts to procure a sufficiently tight binding action of the posts in closing the binder.

It is further an object in this connection 50 to provide an arrangement whereby the flexible connecting posts may be detached manually from the mechanical operating means thereof, to provide for a most ready manipulation under certain conditions.

55 It is still further an object to provide an arrangement whereby the mechanical oper-

ating means for the flexible posts may serve as temporary means for clamping the posts to the receiving head in the manner necessitating but a partial rotation of the feed 60 screw to procure successive clamping and unclamping actuations.

A still further object resides in the provision of a flexible connecting post having a most ready flexure in its single desired 65 direction of flexure.

With the above and other objects and advantages in view, the invention resides more particularly in the novel combination, formation and arrangement of parts herein- 70 after described and pointed out in the appended claims.

In the drawings:

Figure 1 is a horizontal sectional view through a receiving binder head embodying 75 my invention.

Fig. 2 is an end view of a pair of binder heads and a connecting post engageable in one of said heads, the said head being in vertical section as indicated by the line 2—2 80 of Fig. 1.

Fig. 3 is a vertical sectional view through one end portion of said head showing the temporary binding action of the carriage blocks.

Fig. 4 is an elevational view of one of the links of a desired form of flexible connecting post, with an adjacent link associated therewith in section, taken on the line 4—4 of Fig. 5.

Fig. 5 is an elevational view of a pair of such links, looking toward the inner sides thereof.

Fig. 6 is a transverse sectional view through the links on the line 6—6 of Fig. 4. 95

Fig. 7 is a side elevational view of a connecting post flexible in one plane only and avoiding the necessity of providing pivotally connected link sections.

Fig. 8 is an elevational view of a section 100 of said post, looking toward the inner side thereof.

Fig. 9 is a transverse sectional view through this post on the line 9—9 of Fig. 7.

Referring now more particularly to the 105 accompanying drawings, 5 and 6 designate preferably upper and lower binder heads with the usual blocks 7 in their ends. The upper head 5 is preferably of the "spectacle case type" and extended longitudinally 110 through this upper head at one side and journaled in the end blocks 7 thereof is a

feed shaft 8 provided with right and left hand threads and having one end squared and extended into a socket 9 in one of the end blocks 7 for engagement with a suitable 5 key member insertible in said socket. A pair of carriage blocks 10 are disposed in the head 5 and carry the sleeves 11 threadedly engaged on the oppositely threaded portions of the feed shaft. These blocks are 10 held slidably on the bottom of the binder head by engagement of their adjacent sides with a guide rod 12 secured longitudinally in the head at its side opposite the feed shaft. The bottom of the binder head 5 is provided 15 with openings 13 adjacent its ends for the reception of flexible connecting posts 14, the ends of said posts within the binder head being provided with end pieces 15 having their free extremities beveled and each provided 20 with a transversely extending aperture 16 which is adapted to receive a holding pin 17 projecting inwardly from each of the carriage blocks.

Thus upon rotating the feed shaft to move 25 the carriage blocks inwardly, the flexible posts 14 will be retracted to procure a tight clamping action of the binder heads with respect to a body of leaves disposed therebetween, and to permit a ready movement 30 apart of the binder heads to open the binder, the connecting posts may be detached from the carriage blocks for movement independently thereof.

This operation may obviously be effected 35 manually by merely opening the binder head and lifting the end pieces 15 of the connecting posts clear of the pins 17. For effecting this detachment mechanically in a manner which does not interfere with manual detachment, the bottom of the binder head is 40 provided with series of transverse slots 18 substantially forming series of teeth, and pivoted at one end in an opening of each carriage block 10 is a pawl 19 having a spur 45 20 at its pivoted end which projects under the carriage block, and which by engagement in one of the slots 8 upon outward movement of the carriage block is adapted to rock the pawl upwardly and thus strip 50 the end pieces 15 of the corresponding connecting head from the pin 17 of the block. Thus a slight rotative movement of the feed shaft 8 will effect the automatic detachment 55 of the connecting posts from the carriage blocks, and the binder heads may be freely moved apart. In closing the binder, the heads are manually moved together to automatically feed the connecting posts within 60 the receiving head 5, and the carriage blocks 65 10 may be moved to engage their pin 17 in the end pieces of the connecting posts, and then further moved by rotation of the feed shaft to procure a tight clamping action of the binder heads. The aforementioned end 70 bevel of the end pieces facilitates movement

of the clamping blocks to a position thereunder, and for assuring engagement of the pins 17 in said end pieces, springs 21 may be secured to the cover of the binder head. By the provision of slots 18 throughout the 70 major portion of the length of the binder head, provision is made for automatic engagement and disengagement of the carriage blocks with the connecting posts in differing degrees of projection of said post 75 from the head.

For providing a temporary means for holding the flexible posts against movement relative to the head 5, the carriage blocks 10 may be moved outwardly, as shown in Fig. 80 3, for abutting engagement with intermediate portions of the posts, to bind said intermediate portions of the posts against the outer edges of the openings 18. Thus clamping action may obviously be released 85 or applied by a partial rotation of the feed shaft 8, thus procuring an exceedingly ready manipulation.

I have found that the provision of a flexible connecting post comprising pivotally 90 connected links circular in cross section does not provide for a sufficient degree of flexure of the posts, and to increase the flexure of the posts the links are flattened on both sides transversely of the plane of flexure, as shown 95 more particularly at the right hand side of Fig. 1.

I find it desirable in some instances to use flexible posts formed of sheet metal, and Figs. 4 to 6 show a post embodying this 100 construction wherein each of the links is formed of a flat plate of metal having its intermediate portion bent in the form of a cylinder flattened at opposed portions, the side edges of the plate being bent inwardly 105 and being provided with upward extensions 22 offset inwardly to lie in engaging relation between the edge portions of an adjacent link, and being pivotally connected therewith by a pin 23 passed therethrough 110 and through said edge portions and held against displacement by abutment with the sides of the cylindrical body of the link, it being appreciated that this pin is assembled in the link coincident with the bending formation of the cylindrical body of the link. To permit a most ready movement of the body of leaves with respect to the links, the outer portions of the top and bottom edges 115 of the links are inclined at an acute angle 120 to the axis of the links, the inner portions of said edges of the links being curved to permit flexure of the post in one direction only. It is appreciated that a provision for flexure of the posts only at their inner sides 125 is essential in view of the necessity of preventing relative lateral movement of the binder heads.

Figs. 7 to 9 show a still further form of connecting posts which obviates the use of 130

pivotsly connected links. This type of post comprises a lower end piece 24 socketed for suitable securement to a binder head and an upper end piece 25 having in the present instance a socket link 26 pivoted thereto and engageable with a pin 27 carried by a carriage block 28 connected with the feed shaft 8 of the receiving binder head. Connected to these end pieces 25 are a pair of preferably metallic flexible cords 29, and disposed about these cords are a series of sheathing bands 30 which have their end edges disposed in abutting relation. Each of these sheathing bands comprises a plate of metal 15 bent about the pair of cords 29 and having their side edge portions bent inwardly between the cords, with their extremities curved outwardly whereby said cords are held in the band against relative lateral 20 movement. Each of the bands thus presents an oval cross-section. To permit flexure of the post thus provided in a single direction, the edge portions of the bands at the open sides thereof are curvilinearly cut 25 away, the open sides of the bands being disposed inwardly with respect to the assembly of the posts in a binder, and thus the outer sides of the posts present a substantially unbroken curved surface.

30 What is claimed is:

1. A loose leaf binder including a pair of binder heads, flexible connecting posts secured to one head and passed into the other head to extensibly lie therewithin, carriage blocks slidably mounted in the last mentioned head, means for simultaneously moving said carriage blocks in opposite directions and means for detachably connecting said carriage blocks and the flexible posts. 35
 2. A loose leaf binder including a pair of binder heads, flexible connecting posts secured to one head and passed into the other head to extensibly lie therewithin, carriage blocks slidably mounted in the last mentioned head, means for simultaneously moving said carriage blocks in opposite directions, means for detachably connecting said carriage blocks and the flexible posts, and means for automatically procuring detachment of the flexible posts from the carriage blocks upon outward movement of said blocks. 45
 50

3. A loose leaf binder including a pair of binder heads, flexible connecting posts secured to one head and passed into the other head to extensibly lie therewithin, carriage blocks slidably mounted in the last mentioned head, means for simultaneously moving said carriage blocks in opposite directions, pins on said carriage blocks, and end pieces for the flexible posts provided with recesses for receiving the pins of the carriage blocks. 55
 60

4. A loose leaf binder including a pair of binder heads, flexible connecting posts se-

cured to one head and passed into the other head to extensibly lie therewithin, carriage blocks slidably mounted in the last mentioned head, means for simultaneously moving said carriage blocks in opposite directions, means detachably connecting said carriage blocks and the flexible posts, pawls pivoted to the carriage blocks and engageable with the flexible posts to detach said posts from the blocks, and means in the head for engaging said pawls upon movement of the carriage blocks. 70
 75

5. A loose leaf binder including a pair of binder heads, flexible connecting posts secured to one head and passed into the other head to extensibly lie therewithin, carriage blocks slidably mounted in the last mentioned head, means for simultaneously moving said carriage blocks in opposite directions, means detachably connecting said carriage blocks and the flexible posts, pawls pivoted to the carriage blocks and engageable with the flexible posts to detach said posts from the blocks, and series of ratchet teeth in the head engageable with the pawls 90 to rock said pawls. 80
 85

6. A loose leaf binder including a pair of binder heads, flexible connecting posts secured to one head and passed into the other head to extensibly lie therewithin, carriage blocks slidably mounted in the last mentioned head, a feed shaft journaled in the head and pivoted with oppositely threaded sections connected with the carriage blocks, and means detachably connecting said carriage blocks and the flexible posts. 95
 100

7. A loose leaf binder including a pair of binder heads, flexible connecting posts secured to one head and passed into the other head to extensibly lie therewithin, carriage blocks slidably mounted in the last mentioned head, means for simultaneously moving said carriage blocks in opposite directions, means detachably connecting said carriage blocks and the flexible posts, and means for detaching the flexible posts from the carriage blocks comprising pawls pivoted to the carriage blocks, the adjacent wall of the head being provided with longitudinal series of slots, and spurs on said pawls 110 engageable in the slots to rock the pawls. 105
 110
 115

8. A loose leaf binder including a pair of binder heads, flexible connecting posts secured to one head and passed into the other head to extensibly lie therewithin, carriage blocks slidably mounted in the last mentioned head, means for simultaneously moving said carriage blocks in opposite directions, means detachably connecting said carriage blocks and the ends of the posts and 120 said carriage blocks being clampingly engageable with the flexible posts at their junctures with the head. 125
 125

9. In a loose leaf binder, a flexible connecting post comprising end pieces, a flex-

ible core member connecting said end pieces, a series of sheathing members disposed about said core member with their edges disposed in abutting relation and the edge 5 portions of the sheathing members at one side of the post being cut away to permit flexure of the post in one direction.

10. In a loose leaf binder, a flexible connecting post comprising end pieces, a pair of flexible core members connecting the end pieces, a series of sheathing members disposed about the core members and with their edges disposed in abutting relation, each sheathing member comprising a plate bent 15 about the core members with its side edge portions bent inwardly between the core members, and the end edge portions of the sheathing members at one side of the post being cut away to permit flexure of the post 20 in one direction.

11. A loose leaf binder including a pair of binder heads, flexible connecting posts secured to one head and passed into the other

head to extensibly lie therewithin, carriage blocks slidably mounted in the last mentioned head, means for simultaneously moving said carriage blocks in opposite directions, and means for automatically coupling and uncoupling the flexible posts and carriage blocks upon a selective movement of 30 said carriage blocks.

12. A binder post for loose leaf ledgers comprising end pieces, a flexible core member connecting the end pieces, a series of sheathing members incasing the core members having their edges in abutting relation, the abutting edge portions of the sheathing members being spaced apart at one alined 35 point to permit flexure of said posts in one direction only.

In testimony that I claim the foregoing I have hereunto set my hand at Milwaukee, in the county of Milwaukee and State of Wisconsin.

HENRY CHARLES MILLER.
